United States Patent Office

Des. 184,874
Patented Apr. 14, 1959

184,874

COFFEE POT OR SIMILAR ARTICLE

George T. James, San Fernando, Calif., assignor to Glad-
ding, McBean & Co., Los Angeles, Calif., a corpora-
tion of California

Application October 21, 1958, Serial No. 53,075

Term of patent 14 years

(Cl. D44—26)

Fig. 1 is a side view of a coffee pot showing my new design.

Fig. 2 is a perspective view taken from the front thereof.

I claim:

The ornamental design for a coffee pot or similar article, as shown.
